ABSTRACT: An envelope, which is to be folded, is delivered off an endless belt to a set of gripping bars disposed around the periphery of a rotating drum. The gripping bars carry the envelope under a rotating scoring roller which scores the envelope along as many lines, spaced longitudinally of the envelope, as there are folds to be made in the envelope. As the drum revolves, successive portions of the envelope are released by the gripping bars, so that these successive portions bend away from the body of the envelope along the score lines by their inherent resiliency. As each successive portion of the envelope is released, a paddle is advanced toward the drum to engage the released portion and bend it down onto the yet-unreleased part of the envelope to effect a fold. There are as many paddles or deflectors disposed about the drum as there are folds to be made in the envelope. Thus as the drum rotates the envelope is folded into the desired small compass.

ENVELOPE FOLDING MACHINE

The present invention relates to machines for folding envelopes, and more particularly to machines for folding envelopes used in mailing exposed photographic film to processors for development and printing.

Until relatively recently, cloth sacks were used for mailing exposed film rolls to the processor. When a person bought a roll of film, he was supplied with the cloth sack for mailing the roll to the processor after the roll had been exposed. There was a tag attached to the sack bearing the name and address of the processor, and on which the photographer might put his own return address.

Because cloth sacks are expensive, paper envelopes have come more and more into use as substitutes for cloth sacks. One problem with paper envelopes, however, has been to fold them within small enough a compass to go into the box or carton in which the roll of film itself is packed for sale. For the paper envelopes to be practical, they must be folded into the desired compass at high speed.

The primary object of the present invention is to provide a machine which will fold paper envelopes of the character described into the desired compass at higher speed than prior such machines for this purpose.

Another object of the invention is to provide a machine of the character described which will be more compact, and require less space.

Another object of the invention is to provide a machine of the character described which can readily be adapted for folding envelopes of various sizes.

Other objects of the invention will be apparent hereinafter from the specification and from the recital of the appended claims, particularly when read in conjunction with the accompanying drawings.

In the drawings:

FIG. 1 is a fragmentary side elevation showing somewhat diagrammatically a machine built according to one embodiment of this invention;

FIG. 2 is a fragmentary plan view of this machine;

FIG. 3 is a detail view showing in elevation the type of grips for grasping the envelope blank as it is fed into the machine;

FIG. 4 is a section on the line 4-4 of FIG. 3 showing one such grip in erect, open position;

FIG. 5 is a view similar to FIG. 4 but showing the gripper pivoted to operative position;

FIG. 6 is a fragmentary detail view showing gripping position one of the other type grippers used in a set for holding the envelope during folding;

FIG. 7 is a fragmentary view showing one of these latter type grippers moved to released position;

FIG. 8 to 12 inclusive are fragmentary views illustrating somewhat diagrammatically successive steps in the folding of an envelope on the illustrated machine;

FIG. 13 is a more or less diagrammatic view illustrating the drive to the several illustrated parts of the machine;

FIG. 14 is a rear view of an envelope such as may be folded in a machine built according to the present invention; and

FIG. 15 is a view showing the envelope after folding.

Referring now to the drawings by numerals of reference, 15 (FIG. 14) denotes one type of envelope which may be folded on the machine. It is made from a single sheet of paper folded upon itself to provide a front 16, two rear flaps 17 and 18, a bottom flap 19, which is folded over the bottoms of the rear flaps, and glued thereto, and a top flap 20, which is adapted to be fastened over the rear flaps by a conventional winged fastener 21 that is riveted to one of the rear flaps, and that is adapted to be passed through the hole 22 in a pasteboard grommet 23 and in the top flap 20 to secure the top flap in closed position. The grommet is glued to the back of the top flap 20.

The envelopes E, which are to be folded, are delivered one by one from a hopper or other supply source (not shown) onto an endless belt 30 (FIG. 1) with their bottom ends forward.

The belt 30 travels between the two parallel rails 32 (FIG. 2) of a guide member 33 which is suitably supported on the

frame of the machine, and which extends to the vicinity of a drum 34.

Drum 34 is mounted on it a plurality of gripper bars which hold an envelope initially, and then release different parts of the envelope step-by-step progressively to permit the folding operation to be effected. The gripper bars are arranged, in the machine illustrated, in two sets spaced angularly from one another so that two envelopes E can be folded simultaneously as the drum revolves, carrying them through the machine.

10 In the machine shown, in each set of gripper bars there are four gripper bars 36 (FIGS. 1, 6 and 7) and one gripper bar 70 (FIGS. 1, 3, 4 and 5). Each gripper bar 36 has pivotally mounted on it two opposed, laterally-spaced levers 38 and 39 (FIG 6). These two levers are pivoted by means of pins 41 on the associated bar 36. Each lever carries a gripping finger 42 that, when in operative position, extends over the top of its bar 36 in position to engage and hold against the bar an envelope 15 (E). The two fingers 42 of a pair engage the envelope at opposite lateral sides thereof.

15 20 Each lever 38, 39 is forked to straddle a shaft 44 that is journaled at opposite ends in the associate bar 36. Each lever is mounted to pivot in a recess 45 in the bar, and is normally urged to released position by a coil spring 46 that is interposed between one end wall of a recess 45 and the confronting side of the associated lever 38 or 39. Each lever carries a roller follower 48 that is adapted to engage a cam member 50 which is keyed or otherwise secured to the shaft 44 to rotate therewith. The cam member 50 is so shaped that when the shaft 44 is rotated angularly from the position shown in FIG. 6 to that of FIG. 7, for instance, the springs 46 will rock the levers 38 and 39 associated with the shaft to move the gripping fingers 42 upwardly to move them to released positions out of engagement with the envelope resting on the associated bar.

25 30 35 In the embodiment of the invention shown, there are, as previously stated, two sets of grippers mounted on the drum 34. Each set consists of four grippers bars 36 and a gripper bar 70. The bars 70 precede the bars 36 of each set in the direction of rotation of the drum. Each bar 70 (FIG. 3) supports rotatably a shaft 72, which is journaled in the gripper bar 70, and which carries two gripper members 74. Each member 74, as shown in FIG. 3, is generally T-shaped in elevation and carries at its top an elongate gripper portion 76 that is of generally inverted U-shape in cross section and extends longitudinally along and over the associated bar 70.

40 45 FIG. 4 shows a gripper 74 in released position. FIG. 5 shows this gripper in gripping position to clamp an envelope against the plane top surface of the associated bar 70. The envelopes are delivered from the belt 30 into a pair of 50 grippers 74 at the proper time in the cycle of operation of the machine, that is, as a bar 70 rotates with drum 34 into position adjacent delivery belt 30 (FIG. 1). At this time the grippers 74 of a set will be in their open positions (FIG. 4) to receive an envelope and to limit the extent of feed of an envelope into the 55 machine. The portion 77 (FIG. 4) of a gripper 70 acts as a stop.

50 55 60 65 Delivery is timed by two spaced gate members 52 (FIG. 1), which are carried by two parallel, spaced lever arms 54 that are secured to a shaft 56. The members 52 move in the space between guide member 33 and the confronting portion of belt 30, as shown in FIG. 2. When the members 52 are in the position shown in FIG. 1, an envelope is free to pass off belt 30 into an open pair of gripper jaws 70. When the gate members 52 are raised to their upper positions they stop envelopes from moving off conveyor belt 30 into a pair of gripper jaws 70.

60 65 70 75 The movements of the gate members 52 are controlled by a cam 62 and a follower 60. Secured to shaft 56 at one end thereof is a lever arm 58 that carries the roller follower 60 (FIGS. 1 and 2) which is adapted to ride on the periphery of the cam 62. Cam 62 is secured to a shaft 64. This shaft also carries two members 66 (FIG. 2) which overlie the belt 30 and have segmental enlarged diameter portions 67 (FIG. 1) that cooperate with a disc 31 to feed each envelope, at the correct time, off the belt 30 into the opened grippers of the bar 70 which are the juxtaposed to belt 30.

Disposed above the drum 34 is a second rotary drum 80. This drum carries around its periphery a plurality of scoring blades 82 which project radially from drum 80. There are as many blades 82 as there are folds to be made in the envelope.

There are also as many gripping bars 36 in each set thereof as there are score lines in the envelope.

The various grippers are actuated by stationary cams 90, 91, 92, 93, 94 (FIG. 2), respectively, that are fixed to a sleeve 165 which is formed with a flange 166 by which it is fastened to the machine frame 167. These cams 90, 91, 92, 93, 94 engage followers 100, 101, 102, 103, and 104, to operate the grippers 42, 74 through rotation of the several shafts 44 and 72 carried by the bars 36 and 70.

The cams 90, 91, 92, 93, 94 are shaped so that just before each set of grippers reaches the top position in FIG. 1, and after a previously-folded envelope has been delivered onto a conveyor belt 170 to be carried away, all the gripper bars are opened so as to receive a new envelope from belt 30, and then the set of grippers is closed on the new envelope and then the individual grippers of the set release successively as drum 34 rotates to permit folding the envelope.

The folding operations themselves are effected by operation of paddles 110, 112, 114, and 116, which are operated by cams 120, 122, 124, and 126 (FIG. 2) respectively, that are secured to the shaft 95 coaxial with the drum 34 but at the opposite end of the drum from the stationary cams 90, 91, 92, 93, 94.

Each paddle or folding member, such as that shown at 112 in FIG. 2, comprises two thin plates 134 that have concave surfaces 136 (FIG. 1) at their free, outer ends, and that are fixedly secured in a bar 138. Each bar 138 is secured to a rod 140 that is slidable in a housing 142 which is fastened by a bracket 144 to the frame of the machine. A coil spring 146, which surrounds each rod 140, and which is interposed between one end wall of the associated housing 142 and a washer-nut combination 148 tends to move each paddle 134 in one direction to its outward position. A nut 150 threaded on each rod 140 limits the outward movement of the corresponding rod.

Each rod 140 is moved to its forward position by a forked member 152 (FIG. 1), which straddles the associated rod 140 and carries rollers 154 which engage behind the bar 138. Each yoke 152 is secured to a shaft 156 to which there is secured an arm 158 which carries a roller 160 that engages the periphery of the associated cam 120, 122, 124, or 126. Each shaft 156 is journaled in a bearing member 162 that is carried by the associated bracket 144.

In the operation of the machine, the envelope, which is to be folded, is delivered off belt 30 by the gate or stop 52 (FIG. 1) and slides over guide member 33 into engagement with the jaws 74 (FIGS. 3, 4, 5) of that one of the two gripper bars 70 that at that time is carried by drum 34 into position to engage the envelope. In FIG. 1, the gripper bar 70 at the right in the then lower set of gripper bars, is shown rotating upwardly to a position for gripping an envelope that is to be fed off of belt 30, while the bar 70 in the then upper set of gripper bars has already released an envelope E which is still clamped, however, by the gripping fingers of the bars 36 of this upper set.

As each envelope is fed off of belt 30 it enters the jaws 74 of the gripper bar 70 then in position to receive it. As the drum 34 revolves, the roller 100 (FIG. 2), associated with this gripper bar, rolling on the cam 90 rocks shaft 72 (FIGS. 3, 4 and 5) in a direction to swing the jaws 74 of this bar from the position shown in FIG. 4 to that shown in FIG. 5, thereby to grip the envelope adjacent its bottom edge.

As the first of the following gripping bars 36 comes abreast of the envelope, the roller 101 (FIG. 2) associated with that bar, rolling on cam 91 causes the shaft 44 (FIGS. 6 and 7) associated with that bar to rock first in one direction to swing the associated gripping fingers 42 open, as shown in FIG. 7, to allow the envelope to pass beneath them; and then the roller rides down on the cam 91, causing the shaft 44 to rock in the opposite direction to move the associated fingers 42 to clamping position as shown in FIG. 6 to clamp the envelope against the associated bar 36.

As the succeeding bars 36 come abreast of the envelope, the rollers 102, 103, 104 riding on their respective cams 92, 93, 94 first open the fingers 42 associated with the respective bar so that the envelope can feed under these fingers and then close these fingers on the envelope to clamp the envelope against the respective bar.

As the drum continues to rotate, the envelope, which is now gripped by the jaws 74 of bar 70 and by the gripping fingers 42 of the four bars 36 of the group is carried by drum 34 beneath the successive scoring blades of the rotating drum 80 (FIG. 1). The blades 82 of the rotating drum 80 impress parallel score lines on the envelope that are spaced from one another lengthwise of the envelope. These are the lines on which successive folds are to be made in the envelope.

15 The now-scored envelope, still gripped by jaws 74 and fingers 42, is then carried by drum 34 toward the first paddle 110. As it approaches this paddle, cam 90 (FIG. 2) through roller 100 and associated shaft 72 (FIG. 3) causes the jaws 74 of the associated bar 70 to be released (rocked from the position of FIG. 5 to that of FIG. 4), allowing the bottom portion of the envelope to raise up along its first score line, as shown in FIG. 1. The paddle 110 propelled by associated fork 152 through operation of cam 120 and associated lever 158 is projected in front of this slightly raised bottom portion of the envelope 167 (FIG. 1) to intercept the leading (bottom) edge of the envelope. After the leading edge of the envelope slides on the paddle face a short distance, the cam 120 releases the paddle and the paddle moves rapidly outward under actuation of the associated return spring 146 to the position shown in FIG.

As the drum 34 continues to rotate, the fingers 42 of the third bar 36 of the group are moved to released position by cam 93 (FIG. 2), releasing the next section 171 (FIG. 1) of the envelope so that it rises about the fourth score line, through its own resiliency. Paddle 116 is projected into position to engage this newly-released section of the envelope, by operation of cam 126 (FIG. 1), associated roller 160 and shaft 156. While the paddle 114 is still holding fold 169 of the envelope, paddle 116 engages section 171 of the envelope, raising this portion up as shown in FIG. 1.

The roller 160 associated with paddle 114 now rides down on a low spot of cam 124, allowing the associated spring 146 to retract this paddle; and as the drum continues to rotate the folded portion of the envelope rides under paddle 116 and is flattened against the remaining portion of the envelope, completing the folding operation.

After the folded envelope passes the paddle 116, and the clamping member 42 (FIG. 6) on the last gripper bar 36 of the group are released by action of cam 94 (FIG. 2) and roller 104 acting through cam 50, roller 48 and spring 46 (FIGS. 6 and 7), the folded envelope is delivered onto endless conveyor belt 170 (FIG. 1) which passes around the pulley 174. A deflecting member 172, which is fastened to the frame of the machine insures delivery of the folded envelope onto the belt.

The paddles 110, 112, 114 and 116 are disposed about drum 34 so that there is a 45° angle between successive paddles. This enable the paddles to keep the back portion of the envelope tucked in while another fold is being made in the envelope.

The inner position of each paddle is about $\frac{1}{8}$ inch from the periphery of drum 34; and the outer position is from $\frac{3}{8}$ inch to $\frac{1}{2}$ inch from the drum periphery.

The folded envelope may be carried by belt 170 beneath a labeling apparatus, such as disclosed in the U.S. Pat. of William L. Reineman, No. 3,392,638 issued Jul. 16, 1968. This apparatus affixes a label 175 (FIG. 15) to the envelope to seal it folded. Thus it can be inserted into a box of roll film.

As the drum 34 continues to revolve the group of gripping bars 70, 36, 36, 36, 36, which has just completed folding of an envelope rotates into position for the jaws 74 (FIG. 4) of bar 70 to grip a new envelope delivered into the machine by belt 30, and the described folding operation begins anew on this new envelope. Meantime the other group of gripping bars 70, 36, 36, 36, 36 is carrying another envelope around and it is being folded in the manner already described. Thus, with the illustrated mechanism folding operations on two envelopes can be carried on simultaneously.

The various mechanisms can be actuated in timed relation in various different ways. FIG. 13 illustrates one way in which the several parts may be geared together to effect their timed operations. Here the spur or helical gears of the drive are illustrated diagrammatically by their pitch circles. 180 denotes the main drive gear, which may be driven by a motor or other suitable power source. This gear meshes with and drives a gear 182 that is secured to shaft 95 (FIG. 1) coaxially thereof, to drive drum 34 and cams 120, 122, 124, 126 (FIG. 2). Gear 182 drives a gear 184 that is secured to the shaft 186 which carries the scoring roll 80 (FIG. 1). Gear 182 also meshes with and drives a gear 188 which drives gear 190 that is fixed to the shaft which carries the pulley 31 that drives belt 30. Gear 190, in turn, drives gear 192 on shaft 64 which carries cam 66. Gear 188 also drives a gear 194, which is an idler; and this gear, in turn, drives gear 196 which is secured to shaft 198 (FIG. 1) that carries the drive pulley 174 for belt 170. Thus, all the operating parts may be actuated in proper timed relation.

Cams 120, 122, 124 and 126 are larger in diameter than cams 90, 91, 92, 93, 94 (FIG. 2) to avoid interference of the shafts 156 with the bars 36 and 70. The cams 90, 91, 92, 93, 94 may be removably mounted in peripheral grooves in sleeve 165 and may be split rings for quick removal from or assembly to sleeve 165, or these cams may be formed integral with projection 165; and projection 165 may be bolted or otherwise secured removably at one side of the frame 167 of the machine. Likewise, the cams 120, 122, 124, 126 may be split

rings seated in grooves in a cylinder 176 projecting laterally from the side of drum 34, or they may be integral with this cylinder; and the cylinder may be bolted or otherwise removably fixed to drum 34. Either construction permits quick change of cams for different jobs, that is for folding different sizes and types of envelopes.

While the invention has been described in connection with a specific embodiment thereof, it will be understood then, that is it is capable of further modification, and this application is intended to cover any variations, uses, or adaptions of the invention following, in general, the principles of the invention and including such departures from the present disclosure as come within known or customary practice in the art to which the invention pertains and as may be applied to the essential features hereinbefore set forth, and as fall within the scope of the invention or the limits of the appended claims.

We claim:

1. A machine for folding envelopes, comprising:

20 a rotary drum,
a plurality of grippers carried by said drum for gripping an envelope respectively at different points along the length of the envelope,
means for releasing said grippers successively as said drum revolves to release successively different portions lengthwise of the envelope,
a plurality of folding members disposed about said drum, and
means for moving said folding member successively to engage the successively released portions of the envelope to fold said release portions successively upon one another and down on the unreleased portion of the envelope.

25 2. A machine as claimed in claim 1, having additionally means disposed adjacent said drum for scoring an envelope, held by said grippers, at spaced points along its length before any portion of the envelope is released, to provide score lines along which the envelope is subsequently folded.

30 3. A machine as claimed in claim 2, wherein said scoring means comprises a roll having a plurality of scoring blades spaced from one another around its periphery,
the number of said blades being equal to the number of folds to be made in the envelope, and
means is provided for rotating said roll in time with the rotation of said drum.

35 4. A machine as claimed in claim 1, wherein each of said grippers comprises a bar having a rockable clamping member, and a cam and follower are associated with each bar and are operatively connected to the clamping member on the respective bar to move said clamping member to and from operative position during rotation of said drum.

50 5. A machine as claimed in claim 4, wherein there are as many cams as there are bars in a set of grippers for an envelope, and said cams are fixed relative to said drum so that said followers travel on said cams as the drum rotates.

60 6. A machine as claimed in claim 1, having a separate cam for controlling the movements of each folding member, and means for rotating said separate cams in time with the rotation of said drum.

65 7. A machine as claimed in claim 4, having a separate cam for controlling the movements of each folding member, and means for rotating said separate cams in time with said drum.

8. A machine for folding envelopes, comprising:
a rotary drum,
scoring means disposed adjacent said drum to score said envelope at spaced points along its length as the envelope is carried past said scoring means by said drum in its rotation,
means for gripping an envelope at different points along the length of the envelope between score lines to clamp the envelope to the periphery of said drum,
a plurality of folding members disposed adjacent said drum and spaced from one another around the periphery of said drum,

means for releasing different portions of said envelope successively as it approaches said successive folding members successively in the rotation of said drum, and means for moving said folding members successively into operative relation with the successively released portions of said envelope to fold said released portions successively upon one another and upon the unreleased portion of the envelope.

9. A machine for folding envelopes comprising:
a rotary drum,
a plurality of gripper bars carried by said drum and spaced from one another around the periphery of said drum, each gripper bar having thereon a pivoted clamping member for gripping an envelope and movable to and from operative positions,
a plurality of cams mounted coaxially with said drum to rotate therewith and operatively connected to the different clamping members to pivot said clamping members in opposite directions as said drum rotates, to effect movement of the clamping members to and from operative positions,
a plurality of folding members disposed in angularly spaced relation about said drum, and
a plurality of cams mounted coaxially with said drum to rotate therewith and operatively connected to the different folding members to move said folding members to and from operative position.

10. A machine as claimed in claim 9, wherein each folding member has an arcuate face confronting said drum.

11. A machine as claimed in claim 9, wherein said cams are so shaped that when a portion of the envelope is released by a clamping member, a folding member is moved into operative position to engage the released portion of the envelope, whereby as the drum continues to rotate the released portion of the envelope is bent about a score line and is carried under the folding member to be folded flat on the still-clamped portion of the envelope, and the preceding folding member remains in position to hold the released portion of the envelope until it has passed under the leading edge of the next succeeding folding member.

12. A machine for folding envelopes comprising:
a rotary drum,
a plurality of members for gripping an envelope at spaced points along its length,
a plurality of spaced folding members disposed around said

drums,
means for moving said gripping members to and from operative position and effective to release said gripping members successively during rotation of said drum to release successive portions of the envelope successively, and

means for moving said folding members successively toward and away from said drum during rotation of said drum to cause said folding members to engage the successively released portions of the envelope successively to fold the envelope on itself as the drum rotates.

13. A machine as claimed in claim 12, having:

means for feeding an envelope onto said drum for effecting folding of the envelope,
means for moving said gripping member first to released position to receive the envelope and then to operative position to grip the envelope along its length, and wherein the foremost of said gripping members constitutes a stop to locate the envelope precisely on the drum.

14. A machine as claimed in claim 13, having:
a rotary scoring member disposed adjacent said drum angularly in advance of the first folding member, and
means for rotating said scoring member to impress score lines on said envelope along which it will be subsequently folded.

15. A machine as claimed in claim 12, wherein successive folding members are spaced 45° away from each other around the periphery of said drum.

16. A machine as claimed in claim 12, wherein the means for effecting movement of the gripping members to released positions successively comprise a plurality of stationary cams.

17. A machine as claimed in claim 112, wherein:
said folding members are mounted on a stationary part of the machine for movement toward and from said drum in a direction generally radial of the axis of said drum, and the means for moving said folding members comprises a plurality of cams, one for each folding member, and mounted to rotate in time with said drum.

18. A machine as claimed in claim 17, wherein said cams are mounted to rotate with said drum.

19. A machine as claimed in claim 17, wherein the means for effecting movement of the gripping members to released positions successively comprise a plurality of stationary cams mounted coaxially of said drum.
